UNITED STATES PATENT OFFICE.

HENRY BERRY, OF BIRMINGHAM, CONNECTICUT, ASSIGNOR TO THE DERBY SILVER COMPANY, OF SAME PLACE.

DESIGN FOR A CASTER-CRUET.

SPECIFICATION forming part of Design No. 13,691, dated March 6, 1883.

Application filed December 7, 1882. Term of patent 3½ years.

To all whom it may concern:

Be it known that I, HENRY BERRY, of Birmingham, in the county of New Haven and State of Connecticut, have originated and invented a new and useful Design for Caster-Cruets; and I do hereby declare that the following is a full, clear, and exact description thereof, reference being had to the accompanying drawings, forming a part of this specification.

Figure 1 is a perspective view of the design, and Fig. 2 is a horizontal sectional view.

This design has relation to caster bottles or cruets; and it consists, mainly, in the novel octagonal tapering configuration of the main portion of the body of the bottle and of the stopper, the upper and lower portions of the octagonal surface being separated by a horizontal depression extending entirely around the body, as shown in the accompanying drawings.

The letter A designates the bottle, and B the stopper. The lower portion of the bottle may be of ordinary form, and the neck portion may have any ordinary shape, or that which is illustrated.

The upper or main portion, C, of the body, above the shoulder D, is octagonal, the general form tapering from the shoulder upward.

The plane facets of the octagonal surface are

alternately narrow, as shown at E, and broad, as shown at F.

A depression, G, extends horizontally around the portion C of the bottle, separating the upper and lower octagonal surfaces. This depression is usually curved in concave form from the upper edge of the lower octagonal surface to the lower edge of the upper octagonal surface.

The body of the stopper is of similar configuration, except that the octagonal portion tapers downward, as shown in the drawings.

Having illustrated and described this design, what I claim and desire to secure is—

The design for a caster bottle or cruet, the same consisting of the octagonal tapering contour of the main portion of the body of the bottle and of the stopper, and the concave depression extending entirely around the octagonal portion and separating it into upper and lower octagonal portions, as shown and described.

In testimony that I claim the foregoing as my own I affix my signature in presence of two witnesses.

HENRY BERRY.
